UNITED STATES PATENT OFFICE.

RODOLPHE W. E. CHRISTESEN, OF NEW BRITAIN, CONNECTICUT, ASSIGNOR
TO THE RUSSELL & ERWIN MANUFACTURING COMPANY, OF SAME PLACE.

DESIGN FOR THE ORNAMENTATION OF BUILDERS' HARDWARE.

SPECIFICATION forming part of Design No. 20,895, dated June 30, 1891.

Application filed June 5, 1891. Serial No. 395,271. Term of patent 14 years.

To all whom it may concern:

Be it known that I, RODOLPHE W. E. CHRISTESEN, a citizen of the United States, residing at New Britain, in the county of Hartford, 5 and State of Connecticut, have invented and produced a new and original Design for the Surface Ornamentation of Builders' Hardware, of which the following is a specification, reference being had to the accompanying drawings, forming part thereof.

Figure 1 is a front elevation of a knob and lock escutcheon-plate, showing my design. Fig. 2 is a front elevation of a pair of hinge-leaves, showing my design; and Fig. 3 is a perspective view of a door-knob, showing my design.

The leading feature of my design consists of alternate scroll-shaped grooves with broad bands between them, the same being arranged 20 to radiate from the central portion of a panel or analogous surface, as shown on the escutcheon-plate in Fig. 1, on the knob in Fig. 3, and on the panels of the hinge-leaves in Fig. 2.

25 *a* designates the central portion of the surface that is ornamented with my design, and from which portion narrow grooves *b c*, which are gradually widened toward the outer edge of the surface ornamented, radiate in the form 30 of scrolls. The grooves *b* in their wider portion are ornamented by a series of transverse bars, as shown. The space between the grooves *b* and *c* is in the form of broad bands,

with the surface at their wider portions slightly curved or waved, as shown. This 35 ornamented surface embodying my design may occupy the entire front of a plate—as, for instance, the escutcheon-plate, Fig. 1—or it may be on a panel surrounded by any suitable border, as on the hinge-leaves in Fig. 2, 40 or it may be on the surface of a knob, as shown in Fig. 3. These examples are sufficient to show how it may be applied to a full line of builders' hardware without either showing or specifically naming the various 45 articles comprised in said line. The ornamentation of the surface other than that having the design specifically described is not essential and does not form a part of the design herein sought to be protected; but of 50 course when my design is used in connection with other ornamentation the same should harmonize.

What I claim is—

The design for surface ornamentation of 55 builders' hardware herein shown and described, the same comprising a surface having the narrow grooves *b c*, radiating from a given center in scroll form with broad bands between, and the alternate grooves *b c*, ornamented by a series of rounded ornaments and 60 series of transverse bars, as set forth.

RODOLPHE W. E. CHRISTESEN.
